UNITED STATES PATENT OFFICE.

JOHN WM. MCKINLEY, OF WASHINGTON, DISTRICT OF COLUMBIA.

ADJUSTABLE WINDOW-SHADE HANGER.

1,048,089.

Specification of Letters Patent. Patented Dec. 24, 1912.

Application filed May 31, 1912. Serial No. 700,742.

To all whom it may concern:

Be it known that I, JOHN WILLIAM MCKINLEY, a citizen of the United States, residing at Washington, in the District of Columbia, have invented certain new and useful Improvements in Adjustable Window-Shade Hangers, of which the following is a specification.

Figure 1 is a front elevation of the hanger for an adjustable window shade, embodying my invention. Fig. 2 is a plan view of the same, portions of the roller being shown in dotted lines, and parts of the window casing being shown in horizontal section. Fig. 3 is an elevation looking toward the left hand bracket, the connecting rod being shown in section. Fig. 4 is a similar view looking toward the right hand bracket. Fig. 5 is a section on line V—V, Fig. 1. Fig. 6 is a section on line VI—VI, Fig. 1. Fig. 7 is a front elevation of a modification. Fig. 8 is a plan view of the same. Fig. 9 is a section on the line IX—IX, Fig. 7. Fig. 10 is a section on line X—X, Fig. 7.

Referring to the drawings:—1 and 2 are the bearing brackets for the shade roller 3, the latter being shown in dotted lines. Any suitable roller and shade may be used. The roller indicated is of the known Hartshorn type, having a round pivot 4 mounted in the bearing 5 of the bracket 2, and a squared non-rotary pivot 6 mounted in the squared bearing 7 of the bracket 1. The roller is connected with the pivot 6 by a winding-up spring not shown, the arrangement and operation of which is well known.

8 is an adjustable connecting rod extending across the window parallel with the roller and uniting the brackets 1, 2. This rod is adjustable on the brackets toward and from the axis of the roller, according to the diameter of the latter with the shade rolled up thereon; and is also longitudinally extensible to suit the length of the roller and width of the window. The latter adjustment is effected by making the rod 8 in a plurality of sections slidable on each other and clamped together. In the construction shown the rod is composed of end sections 9 and 10 attached to the brackets, and an intermediate section 11 on which the end sections are longitudinally adjustable. The several parts 9, 10 and 11 are caused to be kept in line with other, preferably by being made of suitable cross-sectional shape. As shown, each of the said parts is of U-shape

in cross-section, having a concave and convex bend 12 and flanges 13. This shape also adds stiffness to the rod as a whole. This particular cross-sectional shape is not, however, essential.

14 indicates clips which hold the sections 9 and 10 to the section 11, being situated where said sections lap on each other as shown. Any suitable number of clips are employed, two being illustrated. The invention includes the idea oflapping directly on each other and uniting the end sections 9 and 10 (Fig. 11) without the use of the intermediate section 11. The clips 14 fit tightly on the rod-sections so as to firmly hold them in place after they have been forced longitudinally to the desired places of adjustment. The clips need not entirely inclose the rod, being by preference formed with flanges 15 which inclose the rod flanges 13. The flanges 15 have a spring action, yielding to permit the described longitudinal adjustment of the rod-sections and also pressing them together laterally.

The brackets 1, 2 are connected with the rod-sections adjustably as by tongues 16 on the brackets beneath which fit laterally turned feet 17 on the rod sections. By sliding the feet 17 beneath the tongues 16, toward or from the axis of the roller, the connecting rod may be properly adjusted relative to the roller, according to the diameter of the roller. The tongues 16 have a spring action, yielding to permit such adjustment and thereafter firmly holding the feet 17 to the brackets. The parts of the rod 8 not being able to rotate on each other, the brackets are kept with their bearings in proper alinement. The brackets are suspended by cords which pass through pulleys or eyes (not shown) at the top of the window, and descend to a cord-holding device at one side of the window, so that the brackets, roller and shade may be vertically adjusted in a known manner to cover or to leave exposed the upper or lower parts of the window, as may be desired. Portions of such cords are shown at 18, knotted at 19 to the bracket. The center of gravity of the whole suspended device, including the roller and shade, varies accordingly to the lateral adjustment of the connecting rod, the material of the shade and the length of the roller, and the points of suspension of the brackets are accordingly made variable. This is preferably accomplished by forming the brackets

with forwardly and backwardly extending slots 20, and the cords are secured at such points in these slots as will effect an average balance of the whole device.

21 indicates teeth along the upper sides of the slots 20 which keep the suspended cords from slipping from their adjusted position. Variable points of attachment for the cords may be furnished by a series of 10 holes 22.

The device is or may be directed as it is hoisted and lowered by guides arranged to engage with a corner of the window casing, such as are shown at 24. These guides may 15 be mounted and adjustable on the rod 8 as shown at 23 (Figs. 1 to 4 and 6), or may be formed directly on the brackets 1, 2 as shown at 23' (Figs. 7 to 10). The latter style of fixture is adapted for what are known as inside shades, which are arranged within the window casing close to the sash. The former 20 style of fixture is adapted for outside shades, which are hung farther away from the sash and on the face of the window casing. The guides 23' are adjusted laterally to fit the casing by sliding the sections of the rod 8, and the roller is thereafter made of suitable 25 length. The guides 23 may be adjusted according to the width of the window opening 30 independently of the brackets by sliding them (the guides) on one or both of the rod sections 9 and 10; the brackets having been adjusted to suit the roller.

The guides 23 are formed with spring 35 tongues 25 which tightly clasp the flanges 13 of the rod sections 9 and 10.

The roller, having a shade or curtain wound thereon, may be applied to the fixture by placing its pivot 4 in the bearing 40 hole 5 of the bracket 2 and moving the bracket 1 toward the roller pivot 6, by the sliding of the parts of the rod 8, until the bearing 7 passes over the pivot 6. It is thereafter impossible for the roller to jump 45 out of the brackets under any impulse of the roller spring, as sometimes happens when one of the roller pivot bearings is left open at the top.

The fixture can be designed for various 50 widths of windows, but any one fixture is capable of extension and retraction for a distance nearly equal to the sum of the lengths of the end rod-sections 9 and 10. For a very narrow window, say one of ten 55 inches, these end sections will each be made about five inches long. With an intermediate section of ten inches length, this fixture will be extensible to about eighteen inches. With end sections of nine inches length 60 windows of widths from eighteen inches to about twenty-five inches can be fitted. Windows of greater widths can be fitted by the

same end sections, using however, any desired length of intermediate section. Such details can be varied according to the 65 dictates of convenience and economy.

What I claim is:—

1. In an adjustable window shade hanger, the combination of the vertically movable brackets having bearings for the roller pivots and having bent-over tongues 16, and rod sections adjustably connected together and having at their ends laterally turned feet 17 adapted to fit adjustably beneath the 70 said tongues, substantially as set forth. 75

2. In an adjustable window shade hanger, the combination of vertically movable brackets having bearings for the roller pivots and means for adjusting suspending cords horizontally along the brackets, and rod sections 80 longitudinally adjustable on one another and adjustable horizontally forward and backward on the said brackets, substantially as set forth.

3. In an adjustable window shade hanger, 85 the combination of vertically movable brackets having bearings for the roller pivots, and rod sections connecting the brackets and longitudinally adjustable on one another, the said brackets having means for adjusting 90 suspending cords horizontally along the brackets consisting of toothed slots whereby suspending cords may be connected directly to the brackets and securely held at their points of adjustment, substantially as set 95 forth. 95

4. In an adjustable window shade hanger, the combination of vertically movable brackets having bearings for the roller pivots, and rod sections connecting the brackets and longitudinally adjustable on one another, the 100 brackets having extending beyond them, longitudinal guides 23' forming angles with the brackets, for direct engagement of the window casing in the said angles, substantially as set forth. 105

5. In an adjustable window shade hanger, the combination of vertically movable brackets having bearings for the roller pivots, means for adjustably suspending the said 110 brackets directly from the window casing, and rod sections connected with and carried by the brackets and longitudinally adjustable on one another, the rod sections being horizontally adjustable toward and 115 from the said bearings of the brackets, substantially as set forth.

In testimony whereof I affix my signature in presence of two witnesses.

J. WM. MCKINLEY.
